Eva McCutcheon.

BY
Collard & McClellan
ATTORNEY

UNITED STATES PATENT OFFICE.

EVA McCUTCHEON, OF BROOKLYN, NEW YORK.

ALUMINUM WARDROBE TRUNK.

Application filed August 15, 1924, Serial No. 732,154. Renewed November 19, 1928.

This invention relates generally to trunks, having more particular reference to a trunk of the type generally known as wardrobe trunks, the invention having for an object 5 the provision of a novel and improved trunk of great durability, a further object relating to the division of the trunk into drawers or compartments separated from one another in a manner to prevent transmission of accidental fire from one compartment to the other, and having further a novel form of secret compartment.

For further comprehension of the invention, and of the objects and advantages 15 thereof, reference will be had to the following description and accompanying drawing, and to the appended claim in which the various novel features of the invention are more particularly set forth.

20 Fig. 1 of the drawing is a face view of my improved trunk with the cover thrown back.

Fig. 2 is a part side view and part longitudinal sectional view taken on the line 2—2 of Fig. 1.

25 Fig. 3 is a longitudinal sectional view at right angles to Fig. 1 and taken on the line 3—3 of Fig. 2.

My improved trunk is preferably made of 30 aluminum and comprises a body portion consisting of the bottom 10, end walls 11, and the side walls 12, these walls being of sufficient thickness to enable the trunk to stand rough usage during handling in transportation from one place to another. The cover is hinged to the body by means of the hinges 14 and comprises the top 15 and the depending flange 16.

In the body of the trunk I provide a number of drawers. As here shown there are 35 five large drawers 17 which extend the full width of the trunk, and three smaller drawers of which one, indicated specifically at 18, is the same depth as the larger drawers while the other two, indicated specifically at

40 19 are arranged at one side of the drawer 18 and are of a combined depth equal to that of the drawer 18. The various drawers may be separated by the usual members 20 on which they are slidably mounted, and as will 45 be understood, are arranged to open toward the front of the trunk, that is to say, the top of the trunk when the latter is lying flat, and are shown as provided with the usual knobs.

To provide a secret compartment for 50 jewelry or other valuables the drawer 18 is

spaced a slight distance from the adjacent end, which end constitutes the top of the trunk when the latter is on end in position acting as a wardrobe, this distance being considerably less than the depth of the drawer 60 so as to fail to attract notice, a partition element 25 closing the space between the end wall of the trunk and the front wall of the said drawer 18. In the space above the drawer I locate a secret receptacle which is 65 shown at 26 and which is hinged to the back, or bottom, wall of the trunk as at 27 and at its front end behind the partition 25 as shown. Slidably mounted on the free end of this receptacle 26 is a locking bolt 28 which 70 is normally held in engagement with a keeper notch in the partition 25 by means of a coiled tension spring 29 which is connected at one end to an upturned lug 30 on the bolt and at its other end to the guide 75 strap 31 fixed to the bottom of the drawer and which straddles the bolt. Formed in the bolt is an aperture 32, while an elongated aperture 33 is formed in the bottom of the receptacle 26 and registers with the aperture 80 in the bolt. When the drawer 18 is moved out a suitable tool can be inserted under the receptacle 26 and engaged with the aperture 32 in the bolt and the latter unlocked, allowing the receptacle to swing down to expose its front end for insertion or removal of valuables. The bolt 28 may be enclosed in a space separated from the body of the receptacle 26 by means of a housing 35. In order to provide sufficient depth in the receptacle 26 to receive articles of fair size, I 85 preferably cut down the height of the back wall of the drawer 18 and lower in correspondence the bottom of the receptacle 26 at the rear end of the latter, this construction 90 as will be apparent providing increased depth without increasing the distance between the top of the drawer 18 and the wall of the trunk.

The cover is provided with aluminum garment hangers 40 arranged to slide back and forth on the side guides 41, and a bag 42 to hold soiled clothes is also provided, while to hold a shoe bag or the like a cruciform member 43 is mounted on the racks 44 extending 105 along the sides of the trunk cover. In addition a hat holder 45 is also provided in the cover.

Having thus described my invention, what I claim as new and desire to protect by Let- 110

ters Patent of the United States is as follows:—

In a device of the class described the combination with a trunk comprising a top wall and spaced side members, of a depending cross support rigidly secured to the top wall and to the spaced side members of said trunk for retaining said side members in spaced relation, a plurality of superimposed drawers, the upper edge of the uppermost drawer being adjacent the lower edge of said depending cross support when said drawer is closed, a pivotally mounted tray comprising a substantially flat bottom side and rear walls and an open forward end disposed be-

tween the top of said trunk and said uppermost drawer forming a concealed chamber therebetween, and locking means comprising a spring pressed bolt mounted on the upper surface of said flat bottom and adapted to extend in advance of the forward edge thereof, said cross support being provided with a recess for receiving the extended end of said bolt positioned to retain the forward edge of the flat bottom of said tray concealed behind said cross support and the open end of said tray closed by said cross support. 25

In testimony whereof I have affixed my signature.

EVA McCUTCHEON.
